UNITED STATES PATENT OFFICE

168,533

COMBINED DISPLAY CASE AND ORDER BOX

Clyde E. Chamberlain, Medford, Oreg., assignor to Gift Service, Inc., Medford, Oreg., a corporation of Oregon

Application May 17, 1952, Serial No. 19,770

Term of patent 14 years

(Cl. D80—11)

To all whom it may concern:

Be it known that I, Clyde E. Chamberlain, a citizen of the United States of America, residing at Medford, county of Jackson, State of Oregon, have invented a new, original, and ornamental Design for a Combined Display Case and Order Box, of which the following is a specification, reference being had to the accompanying drawing, forming part hereof.

Fig. 1 is a front perspective view of a combined display case and order box showing my new design;

Fig. 2 is a front elevation on a reduced scale;

Fig. 3 is a plan view;

Fig. 4 is a left end elevation;

Fig. 5 is a right end elevation; and

Fig. 6 is a rear elevation thereof.

I claim:

The ornamental design for a combined display case and order box, as shown.

CLYDE E. CHAMBERLAIN.
